UNITED STATES PATENT OFFICE.

JOSEPH BECKER, OF WASHINGTON, DISTRICT OF COLUMBIA.

AUTOMATIC-FOCUSING CAMERA.

1,142,295.

Specification of Letters Patent. Patented June 8, 1915.

Application filed August 26, 1911. Serial No. 646,185.

To all whom it may concern:

Be it known that I, JOSEPH BECKER, a citizen of the United States, residing at Washington, in the District of Columbia, 5 have invented a new and useful Improvement in Automatic-Focusing Cameras, of which the following is a specification.

The present invention relates to automatic focusing cameras of the type disclosed 10 in my two prior applications, Case K and Case O, Serial Nos. 269,048 and 542,842, respectively, filed July 10, 1905, and February 9, 1910; and it is based on my discovery 15 that a perfectly circular cam or simple eccentric may serve as focusing gear either in place of, or in coöperation with, the focusing linkages of the said prior applications, Cases K and O which have since become Patents 1,103,342 and 1,103,343. The present 20 application has been identified for convenience of cross reference as Case T.

In the accompanying drawings Figure 1 is a vertical longitudinal section of a camera 25 similar in all essential features to the camera shown in Figs. 19 to 22 of the said prior applications, but specially adapted to be actuated by an eccentric instead of by a linkage. Fig. 2 is a plan of the said eccentric with a diagram of the connections between 30 it and the four focal planes P, F, F', P' of the camera. Fig. 3 is a diagram to illustrate the geometrical principles involved. Fig. 4 is a partly diagrammatic illustration 35 of a "complete form" in which the mechanism determines (as in the complete form Fig. 3 of my said prior applications) two co-varying space elements AD, D'A' which correspond directly to the Newtonian space elements PF, F'P' of the lens. Figs. 5 and 40 6 show the same structure as Fig. 4, but in two other phases; and Fig. 7 is a "simple form" derived from the above "complete form." Figs. 8 to 15 are explanatory diagrams all drawn to the scale shown under 45 Fig. 15.

Referring to Figs. 1 and 2, the bed of the camera comprises two parallel rails 11 mounted on and firmly connected with a heavy base 12 by means of two end supports 50 13 which are bolted to the base 12 by four bolts 14 and riveted to the rail ends. Only one of the two supports 13, one of the four fastening bolts 14 and one of the two rails 11 can be seen in the drawing.

55 At their middle part the rails 11 are connected by a cross bar 16, which is perforated vertically at its middle point, and this bore

15 is continued through the base 12 to form a bearing for a pintle 17 which is riveted to a radial arm 18. This arm 18 fits smoothly 60 in the radial slideway 40 of a circular disk 19 whose geometric center is indicated by the dot C, Fig. 2. Disk 19 may be clamped on arm 18 in any desired radial adjustment by tightening the clamp screw 20 which is 65 threaded into arm 18, but passes freely through the clamping jaw 21. The disk 19 is, furthermore, provided with a peripheral cylindrical flange or rim 22 which engages with the correspondingly curved jaws 23 of 70 the pintle 24 on one side and pintle 34 on the other. Pintle 24 is revolubly held in carriage 25 by a split-pin 26 so that its jaws may slightly turn to follow the varying inclinations of the revolving cam rim 22, and it 75 is adjustably connected with the object frame O by a clamp bolt 27, as fully set forth in said prior applications. Pintle 34 is similarly held in carriage 35 by a split pin 36 and is adjustably connected with the image 80 frame I by a clamp bolt 37.

The pintles 24 and 34 are set or adjusted in proper relation to their respective frames by focusing on infinity, as fully explained in my said two prior applications and the connecting gear is adjusted, also as in the said prior applications, by focusing one of the 85 two end frames I or O on the other.

In the present instance the focusing of I on O or of O on I is most easily performed 90 by adjusting the eccentricity CD of the eccentric. This adjustment can be made in any angular position of the disk 19, but it is most easily done by first setting the disk 19 so that its center C shall lie in the plane 95 determined by the axes A, D, A' of the three pintles 24, 17 and 34. This sets and holds the two end frames O and I at their greatest separation when they must yield the greatest possible enlargement; if C be 100 set between D and A', as shown in Fig. 2; or the corresponding smallest possible reduction, if C be set between D and A.

Having loosened clamp screw 21, the two 105 end frames O, I with the annular rim 22 connecting them are slid along longitudinally while the lens frame L remains stationary, and in this manner one of the end frames may be focused on the other while the same movements properly vary the eccentricity CD of the eccentric by moving center C with relation to axis D.

When the sharpest focus has been obtained, clamp screw 21 is tightened and the

camera is ready for use. The end frames are now moved by turning the disk 19, and this keeps the image at all times sharply in focus while causing it to vary in size.

- 5 Considering the cam disk in the position of Fig. 2, it will be noticed that clockwise rotation through just one-half a turn, or two right angles, causes the value of the copying factor n to vary from its maximum 10 value down through all intermediate values to the minimum, and that during this half turn the upper half of the cam strictly belongs to the image plane P' , whereas the lower half belongs to the object plane P .
 15 The cam disk 19 is, therefore, really composed of two distinct cams, a fact that will become still more evident in considering the "complete form" of Figs. 8 to 10.

20 *Theory of the device.*—The axis D of the eccentric shaft 17 may be considered as being directly and invariably connected with the principal focal planes F, F' of the lens by stays x, x' , as indicated in Fig. 2. Similarly, the axis A of pintle 24 is virtually connected 25 to the object plane P by a bar of length m ; and axis A' of pintle 34 to the image plane P' by a bar of length m' .

30 In focusing on infinity, as will be seen on referring to the said prior applications, m and m' are adjusted to be precisely equal to x and x' and as a result the variable lengths AD, DA' and PF, F'P' are connected by the 35 equations

$$PF = AD \quad (1)$$

$$F'P' = DA' \quad (2)$$

40 in which the values AD and DA' are varied and determined mechanically by the disk 19, which may be considered (Fig. 3) as a perfect circle of radius CA₃ = r pivoted at D.

45 When the eccentric is set as in Figs. 2, AD and DA' are, respectively, equal to the segments A₁D and DA₁' of the longest or diametral chord A₁A₁' in Fig. 3; and the 50 operation of focusing the one end frame on the other has made the product PF.F'P' or its equivalent, AD.DA' equal to f^2 (the second power of the focal length of the lens).

55 Revolving the eccentric of Fig. 3 to bring chord A₂A₂' into the camera axis changes the values of AD and DA' to A₂D and DA₂', and, in view of what precedes and of a well known proposition of geometry, we have

$$A_2D.DA_2' = A_1D.DA_1' = f^2 \quad (3)$$

60 That is to say: The two segments of any chord through D form a product that is not only constant, but also equal to the second power of the focal length of the lens used. 65 This proposition is also true for the shortest chord A₃A₃' which is perpendicular to the diametral chord and is divided by D into equal segments so that these segments must each be equal to f . It is, therefore, seen that the adjustment of the eccentricity e (Fig. 3) has

simply set the eccentric to make one-half of its shortest chord through D equal to the focal length f of the lens used.

The right angled triangle CDA₃ in Fig. 3 directly yields the equation

$$e = \sqrt{r^2 - f^2} \quad (4)$$

which gives the value of the eccentricity e by calculation, if desired, when r and f are known, and from which it appears that r must, in any case, be greater than f .

Designating the maximum value of the copying factor by $n_{(\max.)}$ and its minimum value by $n_{(\min.)}$ we have

$$n_{(\max.)} = \frac{r+e}{f} \quad (5)$$

$$n_{(\min.)} = \frac{r-e}{f} \quad (6)$$

80 *Complete forms.*—The exact operation of the device is most easily understood in what I designate as my "complete forms." Fig. 4 is a partly diagrammatic illustration of a "complete" form corresponding to the 85 "complete" form shown in Fig. 3 of the said prior applications. Here two equal eccentrics 50, 51 connected to revolve together by a belt 52 on pulleys 53, 54 have their axes of rotation D and D' directly mounted in the principal focal planes F, F' of the lens. Eccentric 50 acts directly on an axis A in the object plane P and eccentric 51 directly on an axis A' in the image plane P'. A bar 55 is shown to represent the bed and slide-ways of the camera. The copying factor in Fig. 4 is equal to 2.

90 Fig. 5 shows the displacements produced in Fig. 4 by turning the eccentrics clockwise through one-half of a right angle, which 95 changes the copying factor from 2 to 1.662, or approximately five-thirds.

95 Fig. 6 shows the displacements produced in Fig. 4 by turning the eccentrics through a full right angle, the copying factor being reduced to 1.

100 The passage from the complete form, Fig. 4, to the simplest form, Fig. 7, involves three stages illustrated in Figs. 8, 9 and 10 in which unnecessary parts of the cams 60, 61 are suppressed for clearness.

105 The dimensions in Figs. 8 to 10 are:

$$f = FN = N'F' = 12 \text{ cm.}$$

$$FF' = 2f + NN' = 28 \text{ cm.}$$

$$r = CA = C'A' = 15 \text{ cm.}$$

$$e = CD = C'D' = 9 \text{ cm.}$$

$$PF = AD = 8 \text{ cm.}$$

$$F'P' = D'A' = 18 \text{ cm.}$$

$$n = 1.5$$

120

125

110 Moreover, we have, in Fig. 8,

$$CC' = DD' = 28 \text{ cm.}$$

$$m = x = 0 \text{ cm.}$$

$$m' = x' = 0 \text{ cm.}$$

130

and in Fig. 9

$$\begin{aligned} CC' &= DD' = 14 \text{ cm.} \\ m &= x = 4 \text{ cm.} \\ m' &= x' = 10 \text{ cm.} \end{aligned}$$

5. Finally in Fig. 10

$$\begin{aligned} CC' &= DD' = 0 \text{ cm.} \\ m &= x = 4 \text{ cm.} \\ m' &= x' = 24 \text{ cm.} \end{aligned}$$

10. The dotted lines which are added in Figs. 8, 9 and 10 to connect centers C and C' with each other and with their respective terminals A, D, D', A' represent the direct link-
15 age equivalent of the cam gear. Fig. 8 is directly comparable with Fig. 3 of my said Case K, now Patent 1,103,342, where the short links BD, B'D' correspond, respectively, to the eccentricity CD, C'D' of the present cams. In my said Case K the simple form, Fig. 4, is derived from the complete form, Fig. 3, as explained on page 3 of the Patent 1,103,342, by "shifting" the triangle ABD to the right, and the triangle 20 A'B'D' to the left in such manner as to preserve the equality of the Newtonian space elements in equations 2 and 3 of said Case K. This "shifting" of the Newtonian space elements AD, D'A' of the mechanism with 25 relation to the respectively equal Newtonian space elements PF, F'P' of the lens applies here as in said Case K. In present Fig. 9 the necessarily equal shifts of terminals A and D are, respectively, measured by m and 30 x ; and the necessarily equal shifts of terminals A' and D' are, respectively, measured by m' and x' . As in said Case K the equality of the Newtonian space elements AD and PF is dependent upon having at least one 35 of the terminals A or D freely adjustable; and the equality of the Newtonian space elements D'A' and F'P' is dependent upon having at least one of the terminals A' or D' 40 freely adjustable; and the equality is preferably obtained here as in Case K by focusing on right infinity for AD, and on left infinity for A'D'. This is very clearly set forth in present Figs. 12 to 15, where the lens FNN'F' and the Newtonian spaces PF, 45 F'P' of the lens are the same, as in present Figs. 8 to 10. Each of the seven longitudinal space elements m , x , m' , x' , AD, D'A' and DD' that must be accounted for in the mechanism is brought into evidence by having 50 assigned to it a finite positive whole number value which is the same in the four Figs. 12 to 15; but the Newtonian spaces AD, D'A' of the mechanism are purposely shown out of adjustment. Instead therefore 55 of having m equal x and m' equal x' , we have

$$\begin{aligned} m &= 4 \text{ cm.} \\ x &= 8 \text{ cm.} \\ m' &= 12 \text{ cm.} \\ x' &= 6 \text{ cm.} \end{aligned}$$

Now, to make AD equal PF, space AD must be reduced by 4 centimeters, and this reduction can be made by adding 4 cm. to m or by subtracting 4 cm. from x . Hence either m or x must be adjustable in length. 70

At the right the Newtonian space D'A' of the mechanism must be made 6 centimeters longer, and this can be done by shortening m' to make it equal to x' or by lengthening x' to make it equal to m' . Hence the 75 principle established in my said Case K, that at least two of the connecting points must each be freely adjustable on its respective object, lens or image frame.

In Fig. 12 the imaginary bars m and m' 80 are supposed to be the adjustable bars; and the imaginary bars x and x' are supposed to be invariable in length or non-adjustable; and these non-adjustable bars, x , x' , are shown black to distinguish them from the 85 adjustable bars m and m' left white.

In Fig. 13 the adjustable or white bars are m and x ; in Fig. 14 they are x and x' ; and in Fig. 15 they are x and m' .

In Fig. 12 the 2 independently adjustable 90 terminals are A and A'; in Fig. 13 they are A and D'; in Fig. 14 they are D and D'; in Fig. 15 they are D and A'. Where terminals D and D' are merged in a single terminal DD' as in the simple forms the 95 2 adjustable terminals may be either A and A' or A and DD' or DD' and A'. 100

I have stated above in describing the adjustment of Fig. 1 that the adjustment in eccentricity, or determination of dimension 105 CD, could be made in any angular position of disk 19. This is made clear in the diagram figure, Fig. 11, where the terminals A and A' are supposed to have finally been brought into the relative position illustrated, first, by focusing on left infinity, then by focusing on right infinity; thirdly, by focusing P on P', exactly as in my said Case K. In order that this last or third focusing operation shall be as free as possible, to be 110 made at any preferred copying factor, as in Case K, it is better to disconnect the cam entirely at D. In focusing P on P' the radial slot 64 of the cam 62 will then generally be thrown off to one side, as shown, but, as the end frames are temporarily clamped in their last focused relation, the terminals A and A' will hold the center C of the disk 62 in fixed position so that the disk 62 can be slid around in terminals A and A' as if really pivoted at C. By thus turning the disk, counterclockwise in the case illustrated, the radial slot 64 is easily brought back into registration with the bore of pin D to be rigidly connected to pin D. The adjustment is now complete and the temporary clamps used on the end frames 120 can be removed. 125

A difficulty to be grasped is that the 130 equality of the variable Newtonian spaces

AD and PF or D'A' and F'P' is solely dependent upon the equality of the rigid connections m and x or m' and x' ; and vice versa, that the equality of these rigid connections m and x or m' and x' is solely dependent upon the equality of the variable spaces AD and PF or D'A' and F'P'; also that such equalities are not in any way dependent upon the type or form of constant product focusing mechanism that may be used to connect the terminals A, D, D', A'. This can easily be proved in Fig. 12 with the aid of the two auxiliary variables z and z' . Variable z is the variable distance of terminal A from the vertical or focal plane F; and variable z' is the variable distance of terminal A' from the vertical or focal plane F'.

At the left we evidently have

$$\begin{aligned} 20 \quad PF &= m + z \\ AD &= z + x \\ PF - AD &= m - x \quad (7) \end{aligned}$$

That is to say, the difference (PF - AD) between the variable spaces PF and AD is and always remains equal to the difference ($m - x$) that exists between the rigid connections m and x ; and this difference is constant for all values of z as long as no change is made in the said rigid connections m and x .

Similarly, at the right we have

$$\begin{aligned} 35 \quad F'P' &= z' + m' \\ D'A' &= z' + x' \\ F'P' - D'A' &= m' - x' \quad (8) \end{aligned}$$

and, therefore, here also the difference (F'P' - D'A') between the variable spaces F'P' and D'A' is and always remains equal to the difference ($m' - x'$) that exists between the rigid connections m' and x' ; and this difference is constant for all values of z' as long as no change is made in the said rigid connections m' and x' .

45 The constant difference of equation 7 is *nil* when the terminals A and D are in proper adjustment and it is finite when the same terminals A, D are out of adjustment. The constant difference of equation 8 is *nil* when terminals D' and A' are in proper adjustment and it is finite when the same terminals D', A' are out of adjustment. Thus in Figs. 1, 2, 4, 5, 6, 7, 8, 9, 10 and 11, where the terminals A, D, D', A' are properly adjusted,

$$\begin{aligned} PF - AD &= m - x = 0 \\ F'P' - D'A' &= m' - x' = 0 \end{aligned}$$

and in Figs. 12 to 15, where the terminals A, D, D', A' are purposely shown out of adjustment,

$$\begin{aligned} PF - AD &= m - x = -4 \text{ cm.} \\ F'P' - D'A' &= m' - x' = +6 \text{ cm.} \end{aligned}$$

65 Now the sole purpose of having two of

the terminals longitudinally adjustable on their respective frame O, L, I is to make these constant differences of equations 7 and 8 separately equal to zero, so that we shall have, as in Figs. 1, 2, 4, 5, 6, 7, 8, 9, 10 and 11

$$\begin{aligned} PF - AD &= m - x = 0 \\ F'P' - D'A' &= m' - x' = 0 \end{aligned}$$

whence

$$\begin{aligned} 75 \quad PF &= AD \\ F'P' &= D'A' \end{aligned}$$

as required by equations 1 and 2.

At either end of the camera, therefore, equality of the rigid connections implies equality of the Newtonian spaces, and vice versa, so that adjusting to secure the one equality secures both. This is probably the simplest possible explanation of the principle that is involved in the several methods of adjustment which were first disclosed in my said Case K, now Patent 1,103,342, and which is simply reapplied herein for use with a different type of constant product mechanism.

90 Note 1: In all forms shown the lens frame L is supposed to be the stationary frame, but the mechanism determines the relative positions of the three frames, regardless of what may be the absolute motion of any one of the three frames considered by itself. Either end frame O or I may, as well understood in the art, be the stationary frame instead of L and even all three frames O, L and I may be left free to slide on the rails of the camera bed, provided the eccentric axis D or axes D, D' be directly mounted on the lens frame.

95 Note 2: I am aware that Frécot in the *Bulletin de la Société Lorraine de Photographie* for May, 1898, shows in the upper figure of page 109 two different plane cams mounted on the same vertical axis to be used in an enlarging camera as a constituent part of automatic focusing mechanism; but the said two cams are intended to act in opposition on the same end frame of the camera, the one cam to reduce the distance from such end frame to the lens frame, and the other to increase such same distance. This Frécot document will be found fully cited in Note 9, page 8, of my U. S. Patent No. 1,103,342.

What I claim as my invention and desire to secure by Letters Patent is:

1. The combination with a photographic camera, comprising an object support, a lens support and an image support; also automatic focusing mechanism for causing two of the said three supports to move with relation to the third, to produce desired changes in the size of the sharply focused image; such focusing mechanism comprising: first, a rotary cam face curved to conform with a plane curve and having its axis of rotation located to determine a series of

varying radius vectors for varying the separation of the said object and lens supports; secondly, a rotary cam face curved to conform with a plane curve and having its axis of rotation located to determine a series of varying radius vectors for varying the separation of the said lens and image supports; thirdly, connections between the two cam faces for causing them to rotate simultaneously so that the angularly corresponding vectors of the two cam faces shall be brought into action at the same time.

2. The combination with a photographic camera, comprising an object support, a lens support and an image support; also automatic focusing mechanism for causing two of the said three supports to move with relation to the third, to produce desired changes in the size of the sharply focused image; such focusing mechanism comprising: first, a rotary cam face curved to conform with a plane curve and having its axis of rotation located to determine a series of varying vectors for varying the separation of the said object and lens supports; secondly, a rotary cam face curved to conform with a plane curve and having its axis of rotation located, to determine a series of varying radius vectors for varying the separation of the said lens and image supports; thirdly, connections between the two cam faces for causing them to rotate simultaneously so that the angularly corresponding vectors of the two cam faces shall be brought into action at the same time; fourthly, means for adjusting and regulating the said vector lengths as required for different lenses.

3. The combination with a photographic camera, comprising a lens support, an image support, and an object support, and ways adapted to guide two of said supports with relation to the third, of a plane cam plate having its axis mounted perpendicularly to the direction of the ways in fixed relation to the lens support and adapted to act with opposite cam faces on the said object and image supports to move them simultaneously with relation to said lens support.

4. The combination with a photographic camera, comprising a lens support, an image support, and an object support, and ways adapted to guide two of said supports with relation to the third, of a plane cam plate eccentrically pivoted in fixed relation to said lens support and adapted to act with opposite cam faces on said other two supports.

5. The combination with a photographic camera, comprising a lens support, an image support, and an object support, and ways

adapted to guide two of said supports with relation to the third, of a plane cam plate eccentrically pivoted in fixed relation to said lens support and adapted to act with opposite cam faces on said other two supports, 65 the degree of eccentricity of said eccentric being adjustable.

6. The combination with a photographic camera, comprising a lens support, an image support, and an object support, and ways 70 adapted to guide two of said supports with relation to the third, of an eccentrically pivoted circular cam pivotally mounted with relation to the said lens support and adapted to act, with one varying radius vector, on the said object support, and with the oppositely directed co-varying radius, vector on the said image support.

7. The combination with a photographic camera, comprising a lens support, an object support and an image support, and ways 80 adapted to guide two of said supports with relation to the third, of a cam face curved to conform with a plane curve having a varying radius vector, for varying the separation 85 of the said object and lens supports; and a cam face curved to conform with a plane curve having a varying radius vector for varying the separation of the said lens and image supports; and connections to cause such two 90 cam faces to rotate simultaneously; said cam faces having their angularly corresponding vectors proportioned to form a constant product.

8. The combination with a photographic camera, comprising a lens support, an object support and an image support, and ways 100 adapted to guide two of said supports with relation to the third, of a cam face curved to conform with a plane curve having a varying radius vector for varying the separation of the said object and lens supports; and a cam face curved to conform with a plane curve having a varying radius vector for varying the separation of the said lens and image supports; and connections to cause such two cam faces to rotate simultaneously; said cam faces having their angularly corresponding vectors proportioned to form a 105 constant product; also adjustments to permit of changing the vector lengths and value of such constant product as may be required for different lenses.

In testimony whereof, I have signed my name to this specification in the presence of 115 two subscribing witnesses.

JOSEPH BECKER.
